Primary Examiner — Paula Allen Greene(57) **CLAIM**

The ornamental design for noise-canceling headphones, as shown and described.

DESCRIPTION

FIG. 1 is a perspective view of noise-canceling headphones showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the noise-canceling headphones that form no part of the claimed design.

1 Claim, 8 Drawing Sheets(56)
